ILLUMINATED SIGN

Grant L. Fuller, Cleveland Heights, Ohio

Application May 19, 1932, Serial No. 612,276

8 Claims. (Cl. 40—133)

The present invention relates to signs for use on highways in exposed and sometimes isolated locations and, more particularly, to illuminated signs which are visible both night and day. The 5 signs may also be used as wall panels on buildings, etc.

Signs have heretofore been made which are particularly adapted for locations exposed to the weather and also to tampering, the same being 10 of relatively inexpensive and durable construction, such signs being described in United States Patent No. 1,851,323, dated March 29, 1932. These signs, however, have no utility during the night time and it is the aim of the present invention 15 to provide a sign of this same general type which shall be provided with illuminating means and thus convey its message during the night as well as during the day. It will be appreciated that a sign thus located in a more or less distant, ex- 20 posed location must be adapted to resist the action of the elements which would deteriorate the illuminating means if not excluded, and it is also true that such illuminating means must be rendered as inaccessible as possible to unauthorized 25 persons to avoid tampering. Likewise, glass cannot be used for the display surface of the signs since this material might easily be broken by the wind or by tampering. The sign which is 30 the subject of the present invention has, therefore, been so constructed as to reduce the foregoing hazards to a minimum.

It is, accordingly, an object of the present invention to provide a sign having illuminating means so disposed therein as to be difficultly accessible to unauthorized persons. Another object 35 is to provide a sign without glass panels, but which has the transparent characteristic of glass to a sufficient extent to be useful in interiorly illuminated signs. Still another object of the invention is to provide an illuminated sign in which the fragile illuminating means are enclosed against the weather and against vandalism and so mounted as to resist breakage from these 40 sources. A further object of the invention is to provide an illuminated sign which is a self-contained unit and can be operated continuously with only occasional servicing. To the accomplishment of the foregoing and related ends, said invention, then, consists of the means hereinafter 45 fully described and particularly pointed out in the claims.

The annexed drawing and the following description set forth in detail certain mechanism 50 embodying the invention, such disclosed means

constituting, however, but one of various mechanical forms in which the principle of the invention may be used.

In said annexed drawing:

Fig. 1 is a front elevation of the illuminated sign in use; Fig. 2 is a view of one of the panels incorporated in the sign showing the different stages in forming the panel; Fig. 3 is a section through the panel shown in Fig. 2; Fig. 4 is a horizontal section through the sign showing frames and upright; Fig. 5 is an enlarged transverse vertical section taken through the sign shown in Fig. 1; and Fig. 6 is a section through the sign taken along the line 6—6 of Fig. 5.

Referring to Figs. 1 and 4 of the drawing, the sign comprises uprights 7 and 8 of channel iron, to which are attached the side frames 9 and 10 of the sign by means of screws 11, while the opposed frames, such as 12, are attached by screws 13 which may be removed when it is desired to leave these frames free to be swung upon hinges. The frames of the sign consist of wooden members 14 around which are disposed molded sheathing 15 and the display panels 16 are mounted in these frames.

As seen most clearly in Fig. 5, the two halves of the sign are attached by means of hinges 17 at the bottom and one-half of the sign may be swung down to the position 18 when it is desired to gain access to the interior of the structure for 30 repairs or adjustment. Ordinarily, the swingable half of the sign will not have the illuminating means and appurtenant parts mounted therein, but all of these will be disposed on the permanently erect half of the sign. A cover 19 is 35 placed over the top of the sign to hold the two halves together and to provide a weather-tight top, this cover also being provided with locking means if desired.

Referring to Figs. 2 and 3 of the drawing, the structure of the panels 16 which, as previously stated, must not be of glass or similar brittle material, but which must transmit light, is illustrated. Each panel consists of a base of wire screen 20 having on its inner surface a layer of fabric 21, the screen having flattened knees 22, and the mesh thereof being filled with paint or other coating 23 which will fill the screen to present a water-impervious surface, but with parts corresponding to a legend to be displayed left free of paint. The fabric 21 is also coated with a coating material of an opaque nature but with the portions corresponding to the legend left uncoated in order that the screen and fabric 50 55

shall present a surface, the greater part of which is opaque to light when the two have been caused to adhere together by means of the coating material. For the purpose of filling the screen, a 5 paint or lacquer containing pigment and plaster of Paris may be used and for coating the fabric of a vehicle containing a filler such as iron oxide is suitable.

The panel now presents an opaque non-brittle 10 surface formed by the filled screen with areas in which the mesh has been left open. It is now necessary to remove the fabric underlying these areas in order that light may shine through the panel to project the desired message. For this 15 purpose, a resist is applied over the surface of the cloth but with the required characters blocked out so as not to receive the resist. Where silk is used for the fabric layer, an acid-proof varnish 23' may be used for the resist and 20 an acid may then be applied by spraying or other means over the entire surface of the panel or only to the blocked out portions to rot the cloth where the varnish has not been applied and thus match the overlying screen in a regular 25 pattern. Letters blocked out in acid-proof varnish are shown at 24 in Fig. 2 and the etched letters are shown at 25. The acid is then washed off and the panel is ready for use. The result 30 of this operation is that the interiorly disposed illuminating means will shine through the exposed screen where the meshes have not been filled with the coating material and will not shine through the filled screen and cloth which has been rendered opaque by the coating material.

35 It will be appreciated that the screen and cloth construction is not brittle and will receive blows and shocks transmitted by the wind or by meddlers without breaking, as would be the case if glass were used.

40 The screen 20 above described may be of copper, bronze, steel or other metals commonly used in screen construction, but which have been formed or flattened so as to provide flattened knees in the mesh and thus require less coating material to fill the meshes. It is also possible to 45 replace the screen by perforated metal or by a reticulated structure which has been die-cast from some metal such as lead. The fabric used to cover the screen is preferably of thin bolting 50 silk which is readily rotted by acid, but it will be obvious that other fabrics may be used in conjunction with an etching substance which will rot such fabric. Where a cloth which requires a rotting medium other than acid is used, the acid-proof varnish mentioned above will be 55 replaced by a coating which resists such rotting agent. It is also desirable to starch the fabric used in order to render this stiffer and less liable to wrinkle and also to increase its useful life. 60 The fabric may be applied on both sides of the screen in some instances.

In forming the screen and cloth into a composite structure as described above, any suitable method may be followed but it has been found 65 advantageous to apply the opaque filler to the cloth by means of a printing press and then to lay the screen on top of the wet application on the cloth, weighting the screen and letting the 70 filler dry. In this way the cloth will become firmly attached to the screen and the mesh of the screen may then be filled up with a coating material by another operation of the printing press in which a legend is printed on the screen by leaving those portions of the screen corresponding 75 to the legend free of coating. Still another

printing operation can then be used to apply the acid-proof varnish or other resist to the cloth surface leaving areas corresponding to the open-mesh areas of the screen free of varnish so as to be rotted by the acid or other etching substance. The coating material should be applied again if all the meshes in the coated areas are not filled and any projecting material should be rubbed off.

80 The illuminating means for the present structure comprise luminous tubes, such as neon-filled tubes 26, which are mounted inside the sign and supported on the inner side of a panel by means of vacuum cups 27 carrying springs 28 with hooks 29 for the reception of the tubes. Likewise, reflectors 31 are provided which may also be mounted on the sides of the panels by means of suction cups 32. In the case of the reflectors, it is not necessary to provide springs since the reflectors can well withstand any shock transmitted by the wind or other agency. The resultant 85 mounting means for the luminous tubes insulates these from shock or side sway imparted to the sign but, as a further insurance against detachment of the tubes, these are also suspended by 90 means of springs 33 depending from the top of the sign so that, if the tubes should become disengaged from the vacuum cup mounting, they will still be prevented from falling and breaking. Of course, the spring suspension 33 is relied upon 95 only as an emergency holding means since such suspension would not prevent swinging of the tubes against the sides of the panels.

The luminous tubes are disposed in any advantageous manner to illuminate the legend on 100 the panels and such tubes may either be continuous and bent to conform to the legend, or a series of small tubes may be connected electrically, as desired. The source of current for exciting the tubes can be a near-by power line with 105 appropriate transformer where such power line is available, or a battery 34 of cells, such as dry cells, may be disposed within the casing of the sign, together with a transformer 35, including an interrupter, for stepping up the voltage. In 110 order to render the sign more noticeable, a flasher 36 of interrupter or other well-known type may also be disposed within the casing.

The above described structure constitutes a 115 sign having interiorly disposed illuminating means and panels presenting a screen or reticulated surface filled with paint or other opaque covering material and backed with cloth adhering to the screen by means of the adhesive qualities of this covering medium. Letters, characters, 120 or designs may be formed in the opaque surface by omitting the covering material from areas constituting the legend or design and by etching the backing fabric in corresponding areas. The light from the interior illuminating means is 125 effectively transmitted through the reticulated areas corresponding to the legend while the remainder of the panel forms an opaque non-brittle structure which resists the elements and 130 vandalism as contrasted with glass panels which 135 would be readily broken.

The herein described sign is built to withstand 140 hard usage and adapted to give service with infrequent attention and is, moreover, inexpensive to manufacture, where cloth and screen are used, the structure being intended to be used as a roadside sign in outlying locations where it has not heretofore been feasible to provide an illuminated display.

Other modes of applying the principle of my 145

invention may be employed instead of the one explained, change being made as regards the structure herein disclosed, provided the means stated by any of the following claims or the equivalent of such stated means be employed.

I therefore particularly point out and distinctly claim as my invention:

1. A panel for illuminated signs comprising a layer of reticulated material, a sheet of fabric disposed thereagainst, coating material filling the meshes of said reticulated material and coating material impregnating said fabric to form an approximately opaque surface, and areas in said panel from which the fabric has been removed and the reticulated material left unfilled to form light-transmitting characters.

2. A panel for illuminated signs comprising a layer of wire screen, a sheet of silk fabric disposed thereagainst, coating material filling the meshes of said screen and coating material impregnating said fabric to form an approximately opaque surface and areas in said panel from which the silk fabric has been removed and the screen mesh left unfilled to form light-transmitting characters.

3. An illuminated sign comprising a pair of opposed panels of non-brittle, opaque material, frames engaging the margin of said panels and forming a weather-tight structure, light-transmitting, reticulated areas in said panels, a source of illumination of the luminous tube type disposed between said panels, and a source of electric current for the excitation of the luminous tubes also disposed between said panels.

4. An illuminated sign comprising a plurality of panels consisting of a layer of wire screen and a sheet of fabric disposed thereunder, said screen and fabric being impregnated and covered with a coating material to form an opaque and weather-tight surface, areas in said panels from which the fabric has been removed to form light-transmitting characters and corresponding areas in

said screen left free of coating material, and a source of illumination between said panels.

5. An illuminated sign comprising a pair of opposed panels, frames engaging the margins of said panels and forming a weather-tight structure, said panels consisting of a layer of wire screen and a sheet of fabric disposed thereunder, said screen and fabric being covered with a coating material to form an opaque and weather-tight surface, areas in said panels from which said fabric has been removed to form light-transmitting characters and corresponding areas in said screen left free of coating material, and a source of illumination disposed between said panels in said weather-tight structure.

6. An illuminated sign comprising a pair of opposed panels of non-brittle, opaque material, light-transmitting, reticulated areas in said panels, frames engaging the margins of said panels and forming a weather-tight structure therewith, and luminous tubes disposed between said panels and resiliently mounted on the inner sides of said panels and resiliently suspended from said frames.

7. An illuminated sign comprising a pair of opposed panels of non-brittle, opaque material, light-transmitting, reticulated areas in said panels, frames engaging the margins of said panels and forming a weather-tight structure therewith, a source of illumination mounted between said panels, and hinges on said frames swingably supporting one of said panels.

8. A panel for illuminated signs comprising a layer of reticulated material, sheets of fabric disposed on either side of said layer of reticulated material, coating material filling the meshes of said reticulated material and coating material impregnating said fabric to form an approximately opaque surface, and areas in said panel from which the fabric has been removed and the mesh of the reticulated material left unfilled to form light-transmitting characters.

GRANT L. FULLER.
